UNITED STATES PATENT OFFICE.

CARL GABRIELSON, OF SYRACUSE, NEW YORK, ASSIGNOR TO L. C. SMITH & BROS. TYPEWRITER COMPANY, OF SYRACUSE, NEW YORK, A CORPORATION OF NEW YORK.

CARD-WRITING PLATEN FOR TYPE-WRITING MACHINES.

1,160,503.

Specification of Letters Patent. Patented Nov. 16, 1915.

Application filed February 3, 1914. Serial No. 816,257.

To all whom it may concern:

Be it known that I, CARL GABRIELSON, a citizen of the United States, and resident of Syracuse, county of Onondaga, State of New York, have invented certain new and useful Improvements in Card-Writing Platens for Type-Writing Machines, of which the following is a specification.

This invention relates to card holding and feeding devices for typewriting machines and particularly to means for holding and feeding stencil cards, such as are used in addressing machines.

The invention will be described in connection with the accompanying drawing, in which,

Figure 1 is a front view of a typewriter platen and attachments embodying the invention; Fig. 2 is a partial front view, the platen proper and the card holder being removed; Fig. 3 is a sectional view on the line 3—3 of Fig. 1, illustrating the ribbon feeding mechanism; Fig. 4 is a transverse section on the line 4—4 of Fig. 1; Fig. 5 is a rear view of the card holder; Fig. 6 is a rear view of the platen in perspective; Fig. 7 is a view of one of the side frames of the device; Fig. 8 is a perspective view of the lever which carries the ribbon reversing pinions, and Fig. 9 is a view of the platen ratchet.

Referring to the drawing, 10 indicates a platen shaft which is adapted to be received in the platen bearings of a standard typewriting machine and 11 indicates the usual ratchet wheel, fast on the shaft, for rotating the platen step by step. In the present instance a segmental platen 12 is secured on the shaft 10 by suitable set screws. This platen is preferably provided on its face with clips 13 for holding a celluloid plate 14 to provide a suitable and renewable writing surface. The celluloid plate can be removed and another one sprung into place when it is desired to renew the writing surface.

The card holder comprises a U-shaped plate consisting in end pieces 15 and a cross connecting piece 16, together with spring clips 17, which are secured on the back of the end pieces 15 and coöperate with said end pieces to hold the ends of the cards. The spring clips 17 are spaced from the end plates 15 so as to receive the cards and they

are bent inward slightly at 18 to retain the cards in printing position. The lower edge of the card holder is provided with a slight flange 19 adapted to sustain a card in the holder. The card holders are movable up and down, the ends being guided in grooves 20 in the fixed end plates of a supporting frame which will be presently described. The card holder is sustained and moved by projections 21 which engage slots in arms 22 which are rigidly connected to the platen or platen shaft at each end of the platen.

Supported on the platen shaft is a frame comprising end plates 23 which are rigidly connected together by a rod 24 and a curved plate 25. This frame is prevented from turning on the platen shaft by engagement with some fixed portion of the typewriting machine, such as the bar 26.

A ribbon spool 27 is removably supported by the end plates 23 of the fixed frame. As shown in Fig. 2, the ribbon spool has a fixed bearing 28 and a laterally removable bearing 29 which can be withdrawn against the tension of a spring 30 to permit the spool to be removed. The spring plunger carrying 75 the bearing 29 is provided with a knob 31 by means of which the spool may be turned, the bearing 29 being adapted to carry the spool with it when revolved. The spool 27 is provided with a gear 32 which is automatically 80 turned to feed the ribbon in one direction when the platen is moved to space between lines, as will be hereinafter explained.

A second ribbon spool 33 is mounted on the platen shaft within the platen and is 90 free to rotate independently of the platen and shaft. This spool is provided with a gear 34 by means of which it may be automatically rotated, as will be presently explained.

On the rod 24 is the sleeve 35 carrying a gear 36 and a pinion 37. The gear 36 is in mesh with a gear 38 which is mounted on the platen shaft with freedom to revolve independently thereof. The gear 38 is moved 100 upward by means of a pawl 39 when the platen shaft is turned to feed the card holder upward, the pawl 39 being pivoted on one of the arms 22 which carry the card holder. The gear 38 is prevented from 105 moving backward by means of a holding pawl 40, carried by one of the end plates 23. It will thus be seen that each time the card

holder is moved to space between lines the gears 38 and 36 and the pinion 37 will be moved.

The pinion 37 is in mesh with a pinion 41 which, in turn, meshes with a pinion 42, both pinions being carried by an arm of a U-shaped lever 43 which is pivotally mounted on the rod 24. The lever 43 is provided with a handle 43a by means of which it can be shifted to throw the pinion 41 into engagement with the gear of the lower spool 33 or the pinion 42 into engagement with the gear of the upper spool 27. The spools may thus be driven automatically and successively in opposite directions whereby the ribbon is wound back and forth over the printing point. The lever 43 is provided with a spring catch 44 which coöperates with depressions or openings 45 in the adjacent plate 23 to hold the lever 43 in either of its operative positions, for positively feeding either spool.

The ribbon 50 extends from the upper spool down over the face of the platen and thence under a roller 51 and up onto the spool 33, which is mounted on the platen shaft.

As is well known, stencil cards are made by impact of the type directly upon the stencil material and not through a ribbon, as in ordinary typewriting. It is desirable to be able to read the stencil impressions readily, however, and for this reason the ribbon is provided between the stencil and the platen so that an impression will be made on the back of the stencil without affecting the cutting or crushing effect of the bare type upon the stencil card. As but two or three lines are usually written on a card it is only necessary to move the platen shaft back and forth through a small arc and to prevent the platen being moved too far in either direction, and also for the purpose of quickly and accurately locating the first or top line on the stencil card, I provide stops 52 which are fast on the platen shaft adjacent to the ratchet wheel 11 and which coöperate with the usual holding pawl 53 at the back of the ratchet wheel.

Having described my invention what I claim and desire to secure by Letters Patent is,

1. In a typewriting machine, the combination with a platen shaft, of a hollow segmental platen mounted on said shaft, a ribbon spool upon the shaft within the platen, and means for turning the spool to feed the ribbon, said means being operated from the shaft by the turning movement thereof.
2. In a typewriting machine, the combination with a platen shaft, of a hollow segmental platen mounted on said shaft, a rib-

bon spool upon the shaft within the platen, and means for turning the spool to feed the ribbon, said means being operated from the shaft during the forward turning movements thereof only.

3. In a typewriting machine, the combination with a hollow segmental platen, of a ribbon spool within the platen, a second ribbon spool external to the platen, means for guiding the ribbon from one spool to the other over the face of the platen, and means for automatically turning said spools, alternately, to feed the ribbon back and forth over the face of the platen.

4. In a typewriting machine, the combination with a platen shaft, of a hollow segmental platen thereon, a card holder movable with the platen and adapted to hold a card adjacent to the printing point thereon, and means for feeding the ribbon between the card and the platen.

5. In a typewriting machine, the combination with a hollow segmental platen, of a ribbon spool within the platen, a second ribbon spool external to the platen, a card holding device movable with the platen, and means for guiding the ribbon between said card holding device and the face of the platen.

6. In a typewriting machine, the combination with a platen and a card holder movable with the platen, of two ribbon spools, means for automatically turning the spools, alternately, and means for guiding the ribbon between said card holder and the face of the platen.

7. In a typewriting machine, the combination with a hollow segmental platen, a ribbon spool within the platen, means movable with the platen for turning the ribbon spool in one direction, means for limiting the oscillating movement of the platen, and a card holder supported adjacent the face of the platen and movable with the platen.

8. In a typewriting machine, the combination with a platen shaft, of a segmental platen thereon, a card holder adjacent the platen and movable therewith, a ribbon spool within the platen, a ribbon spool external to the platen, and a train of gearing adapted to be connected to rotate said spools alternately, said gearing being driven in one direction by means movable with the platen and said ribbon passing between the card holder and platen.

In testimony whereof I affix my signature in presence of two witnesses.

CARL GABRIELSON.
